UNITED STATES PATENT OFFICE.

OTTO E. GOLDSCHMIDT, OF MONTCLAIR, NEW JERSEY.

APPARATUS FOR HANDLING GRANULAR MATERIAL.

No. 893,479.

Specification of Letters Patent. Patented July 14, 1908.

Application filed December 13, 1907. Serial No. 406,289.

To all whom it may concern:

Be it known that I, OTTO E. GOLDSCHMIDT, of the city of Montclair, county of Essex, and State of New Jersey, have invented certain new and useful Improvements in Apparatus for Handing Granular Material, of which the following is a full, clear, and exact specification, such as will enable others skilled in the art to which it appertains to make and use the same.

My invention relates to an improvement in those apparatus for removing ashes and similar granular material by air pressure, and particularly to those apparatus in which the ashes are deposited first in a receiver and subsequently drawn from the receiver into a cart or other means for disposing of the same.

The object of my invention is to provide means by which the flow of ashes from the receiver may be facilitated and to avoid the clogging of the outlet which would render the air pressure insufficient to start the movement of the ashes. To this end I provide the outlet of the receiver with a nozzle communicating with the outer air which nozzle acts as an inspirator to allow the initial flow of the air and to start the movement of the ashes. I also prefer to combine with this nozzle or inspirator a peculiarly arranged shaker by which the ash may be agitated during the inception of the operation.

The invention involves various other features and all will be fully set forth hereinafter and be particularly pointed out in the claims.

Reference is had to the accompanying drawings, which illustrate, as an example, one manner of embodying my invention.

Figure 1 is a side view of the ash or other receiver with parts in section showing the invention; Fig. 2 is a horizontal detail section on the line 2-2 of Fig. 1; and Fig. 3 is an outline view of the entire system.

In Fig. 3 a typical system is shown in outline in which system the parts are arranged to remove the ashes from a boiler room to the side walk in a cart provided for the reception of the ashes. In this view, 10 indicates the boiler, 11 the blower and *a* the receiver. 12 indicates a cart on the street which is charged with ashes. As will be fully understood from the prior art the blower 11 creates a suction or partial vacuum in the pipe line *b* which communicates with the receiver *a* and cart 12. The suction lines *b'* establish communication between the receiver *a* and cart 12 and also between the

receiver and boiler ash pit as at 14 the soot chamber as at 15 and the floor in front of the boiler as at 16. So that the ashes may be drawn from any or all of these points. The various pipe lines are provided with valves or gates to control them and when it is desired to fill the receiver *a*, the suction connection *b* is cut off from the cart 12 so that the suction created in the pipe line *b* will exert itself in the receiver *a* causing ashes to be turned in to said receiver from the various points 14, 15, or 16 or any of them. When it is desired to charge the cart 12 from the receiver *a* the suction line *b* is opened into communication with the cart 12 and its communication with the receiver *a* is closed with the result that the suction is exerted in the cart 12 and pipe line *b'* connecting the cart with the receiver *a*, the ashes being then drawn through this pipe line from the receiver to the cart. The foregoing it will be understood, is simply an example of one of the various systems in which my invention may be employed. Referring particularly to Figs. 1 and 2, the lower end of the receiver is preferably tapered as at *a'* and fitted therein is a rotatable pipe section *c* having handles *c'* which facilitate manually rocking the section back and forth. The section *c* has connection with the discharge pipe *d* and is preferably provided on its interior as shown best in Fig. 2 with ribs *c*² which serve effectually to agitate the ashes lying in the pipe section. *e* indicates the nozzle which is in the form of an elbow the outer end of which communicates with the atmosphere and the inner end of which is turned down into the pipe section *c*. This nozzle *e* is preferably provided on its exterior with ribs *e'* which assist in the agitating action.

In the operation of this device upon bringing about a partial vacuum in the pipe *d* the atmospheric pressure forces itself through the nozzle *e* and rushes from the same into and through the pipe *d* carrying with it the ashes lying in the pipe section *c*, thus starting the movement of the ashes from the receiver. Should the ashes tend to clog at this point the congestion may be readily broken by oscillating the pipe section *c*. After the operation becomes normal, the pipe section *c* need not be manipulated.

The invention of course may be applied to various other points in the system wherever clogging of the ashes may be liable to occur. Thus it may be and preferably is applied to

the tapered lower end of the ash pit 14 and the invention of course is not limited to the point of application.

When the inspirator nozzle and the rotatable pipe section are applied to the ash-pit, the admission of the air through the inspirator nozzle prevents a diminution of the draft which passes through the grates of the boiler or other furnace, owing to the fact that an amount of air is introduced by the inspirator to take the place of that withdrawn with the ashes.

Having thus described the invention, what I claim is:

- 15 1. A receiver having an outlet through which its contents are adapted to be forced by fluid pressure and also having an inspirator nozzle communicating with the exterior of the receiver and opening into the outlet.
- 20 2. A receiver having an outlet through which its contents are adapted to be forced by fluid pressure and also having an inspirator nozzle communicating with the exterior of the receiver and opening into the outlet, and a movable wall juxtaposed to the nozzle outlet for the purpose specified.
- 25 3. A receiver having an outlet through which its contents are adapted to be forced

by fluid pressure and also having an inspirator nozzle communicating with the exterior 30 of the receiver and opening into the outlet, and a rotatable pipe section surrounding the nozzle outlet and adapted to be oscillated for the purpose specified.

4. A receiver having an outlet through 35 which its contents are adapted to be forced, by fluid pressure and also having an inspirator nozzle communicating with the exterior of the receiver and opening into the outlet, and a rotatable pipe section surrounding the 40 nozzle outlet and adapted to be oscillated for the purpose specified, said nozzle and pipe section having exterior and interior ribs respectively for the purpose specified.

5. A receiver having an outlet through 45 which its contents are adapted to be forced by fluid pressure and a rotatable pipe section in said outlet adapted to be oscillated for the purpose specified.

In testimony whereof I have signed my 50 name to this specification in the presence of two subscribing witnesses.

OTTO E. GOLDSCHMIDT.
